D. MORRIS

TRAFFIC SIGNAL

Filed Feb. 5, 1927

UNITED STATES PATENT OFFICE.

DANIEL MORRIS, OF ST. PETERSBURG, FLORIDA.

TRAFFIC SIGNAL.

Application filed February 5, 1927. Serial No. 166,187.

My invention relates to a traffic signal for use at crossings, turning-points in streets, roadways and the like for the general guidance and control of vehicular traffic without obstructing such traffic, and it is an object of the invention to provide a self-righting traffic signal having a base of the same general size and shape of a paving block, brick, cobble-stone or the like and which traffic signal will return to an upright position facing in a given direction when struck by a vehicle and rocked or tilted on its base and which will not be damaged by any abuse to which it may be subjected, all as will be hereinafter more particularly described and claimed.

Referring to the accompanying drawings which are made a part hereof and on which similar reference characters indicate similar parts,

Figure 1 is a perspective illustrating one application of my invention,

Figure 2, an enlarged detail section,

Figure 3, a perspective illustrating the application of my invention at a railway crossing,

Figure 4, a perspective view illustrating the application of the invention at a street intersection, and

Figure 5, an enlarged composite view.

Figure 6 is a plan view of the device.

In the drawings reference character 10 indicates a substantially rectangular hollow casing having a removable top 11 held in place by screws or other removable fastening means, such hollow casing being substantially the size of an ordinary paving block but if desired may be made in any shape to suit the conditions for which it is to be used. The top 11 is provided with a circular opening 12 in its central portion, such circular opening 12 being preferably inclined from its outer to its inner edge for the reception of a socket member 13. The socket member is provided with a curved inner wall of an elongated shape disposed in a manner corresponding to the dimensions of the top of the casing 10 for a purpose to be hereinafter described. The socket member 13 is also provided with an extension on its underside

which is preferably externally threaded for engagement with internal threads on a cylindrical casing or pipe 14. Any other means for detachably fastening the two parts together may be employed and such casing 14 extends through cap 15 on the bottom of the

casing, such cap being internally threaded for engagement with external threads on the casing 14.

A sleeve 16 is mounted on the casing 14 between the bottom of the casing 10 and the cap 15 on the end of said casing. This structure serves to rigidly maintain the parts in assembled relation. The cap 15 is provided with a central opening 17 within the same in which is mounted a bolt 18 provided with a nut 19 adapted to be operated for drawing the bolt longitudinally through the opening in the cap for adjusting the tension on a spring 20. The upper end of the bolt is provided with an aperture in which is disposed one end of the spring 20, the upper end of which spring is adapted to engage an opening in a bolt 21 projected from the under side of a ball 22 which supports a triangular signal 23. The ball 23 is provided with a slot 24 in its upper portion in which the signal 23 is mounted and such ball is slightly elongated with the elongated portion disposed in parallel relation to the bottom of the V-shaped signal. The cooperating ball and socket joint serve to permit the signal to travel in a substantially vertical plane but permit the ball to be pulled from its socket at substantially right angles to such plane and when released on account of the operation of the spring to be pulled back into normal position.

The casing 14 is sufficiently tight to hold a lubricant and I therefore preferably fill such casing with liquid lubricant which serves not only to lubricate the parts so that they work easily but which excludes water and rust producing agents and prevents disintegration of the structure as a result of water freezing in the casing. Oil may be poured into the casing 14 around the bearing member between the bearing member and its socket. However, in order to facilitate the filling of the casing with oil I provide an orifice 25 and provide a closure plug 26 for such orifice.

In the use of my device a paving block is removed as shown in Figure 1 and the box or casing 10 is inserted in its place. When engaged by an automobile wheel or other device the triangular signal will be depressed sufficiently to permit such wheel or the like to pass thereover. On account of the particular manner of mounting the signal it may readily be moved to a position

substantially parallel with or flat upon the surface of the roadway and will therefore be protected from injury.

In Figure 3 I have illustrated a particular manner for calling the attention of a motorist or other person to a railroad crossing and I preferably provide four signals such as I have shown, three of which are of a medium size and are preferably stationed 10 in equally spaced relation along the center of the roadway and a fourth signal is preferably stationed close to the crossing and in the right side of the roadway. The small signal at the greatest distance from the 15 crossing is preferably provided as shown in Fig. 5 with the word "Stop," the next signal approaching the crossing bearing the word "Look" and the third signal bearing the word "Listen" while the larger signal 20 close to the crossing preferably bears the words "Stop run over me carefully". This last mentioned signal is preferably of a size to extend up above the bumper to a point substantially midway of the radiator of an 25 automobile so that a motorist will be required to slow down in passing over the same. The roadway at the opposite side of the track is provided with similar signals and each large signal adjacent the track is 30 preferably provided on its back, so that it may be viewed from the opposite side of the track, with the warning "Stop run over me 35 carefully", whereby when a motorist or other person approaches the railroad crossing they are given due and timely notice in order to proceed in a cautious manner over the crossing.

In Figure 4 I have illustrated the manner in which my signal may be employed at a 40 road intersection to warn traffic of danger and to indicate certain routes, each signal being capable of indicating direction, either straight ahead or to the right or left.

My signals are preferably all painted in a 45 distinctive manner which will readily attract the eye and may be black and white or any other combination of colors desirable.

It will be obvious to those skilled in the 50 art that various changes may be made in my device without departing from the spirit of the invention and therefore I do not limit myself to what is shown in the drawings and described in the specification, but only as indicated in the appended claims.

Having thus fully described my said invention, what I claim as new and desire to 55 secure by Letters Patent, is:

1. A traffic signal comprising a body in the form of a paving block, an oval shaped 60 socket in the upper portion of said body, an oval bearing member in said socket, a signaling element mounted in said bearing member, and means for holding said signaling element in upright position said socket and 65 bearing member permitting the signal to

rock in a vertical plane and causing it to return to the proper position, substantially as set forth.

2. A traffic signal comprising a body in the form of a paving block, an elongated 70 socket in the upper portion of said body, an elongated bearing member in said socket, a signaling element mounted in said elongated bearing member, means for holding said signaling element in upright position said 75 elongated socket and bearing member permitting the signal to rock in a vertical plane but preventing the signal from swinging in a horizontal plane, and yieldable means holding said bearing member in said socket 80 but permitting the bearing member to be pulled out of the socket when the signal is forced at an angle to the plane at which it is normally adapted to swing, substantially as set forth.

3. A traffic signal comprising a body, an oval shaped socket in the upper portion of said body, a complementary oval shaped bearing member in said socket, a signaling element mounted in said bearing member, 90 means for holding said signaling element in upright position, said socket and bearing member permitting the signal to rock in a vertical direction and causing it to return to the proper position and adjustable means 95 for maintaining said bearing member in its socket but permitting it to be yieldably withdrawn therefrom, substantially as set forth.

4. A traffic signal comprising a body, a casing depending from said body adapted 100 to contain lubricant, an elongated socket in the upper portion of the body over said casing, a complementary bearing member disposed in said socket, yieldable means engaging said bearing member and adjustably 105 connected to said casing normally holding the bearing member in the socket and permitting the same to be withdrawn therefrom, and a signal mounted on the upper portion of the bearing member and adapted 110 to be held in upright position but adapted to be tipped over to permit an object to pass thereover, substantially as set forth.

5. A signal device comprising a base member having an elongated opening therein, a signal element mounted to rest partly within said opening and resiliently held therein, means adapted to permit the signal element to move freely through one vertical plane with but slight displacement from the socket, and means permitting movement in any 115 number of vertical planes by a slightly greater displacement from the socket, substantially as set forth.

6. A traffic signal comprising a body having an oval-shaped socket in the upper portion thereof, a complementary oval-shaped bearing member in said socket, a signaling element mounted in said oval-shaped bearing member, and means for holding said 120 125 130 135 140 145 150 155 160 165 170 175 180 185 190

signaling element in upright position, said oval-shaped socket and bearing member co-operating to permit the signal to rock in a vertical plane and to cause it to return to the proper position, substantially as set forth.

7. A traffic signal comprising a body, an oval-shaped socket in the upper portion of said body, a complementary oval-shaped bearing member in said socket, a signaling element mounted in said bearing member, means for holding said signaling element in

upright position, said oval-shaped socket and bearing member permitting the signal to rock in a vertical plane and causing it to return to the proper position, and means for keeping said bearing member constantly lubricated, substantially as set forth.

In witness whereof, I have hereunto set my hand at Washington, District of Columbia, this fourth day of February, A. D. nineteen hundred and twenty-seven.

DANIEL MORRIS.
